(57) **CLAIM**

The ornamental design for a scabbard with removable knife, as shown and described.

DESCRIPTION

FIG. 1 is an assembled rear perspective view of a knife and scabbard, showing our new design;

FIG. 2 is a front perspective view thereof;

FIG. 3 is a right side elevational view thereof;

FIG. 4 is a front end elevational view thereof;

FIG. 5 is a rear end elevational view thereof;

FIG. 6 is a left side elevational view thereof;

FIG. 7 is a bottom plan view thereof;

FIG. 8 is a top plan view thereof;

FIG. 9 is a rear perspective view of the knife, with the scabbard removed and not shown;

FIG. 10 is a front perspective view thereof;

FIG. 11 is a right side elevational view thereof;

FIG. 12 is a front end elevational view thereof;

FIG. 13 is a rear end elevational view thereof;

FIG. 14 is a left side elevational view thereof, the right side being a mirror image;

FIG. 15 is a bottom plan view thereof;

FIG. 16 is a top plan view thereof;

FIG. 17 is a rear perspective view of the scabbard, with the knife removed and not shown;

FIG. 18 is a front perspective view thereof;

FIG. 19 is a left side elevational view thereof;

FIG. 20 is a right side elevational view thereof;

FIG. 21 is a front end elevational view thereof;

FIG. 22 is a rear end elevational view thereof;

FIG. 23 is a top plan view thereof; and,

FIG. 24 is a bottom plan view thereof.
